UNITED STATES PATENT OFFICE.

JAMES W. NELSON, OF NEW YORK, N. Y.

PRESSURE-CONTROLLING DEVICE FOR HYDRAULIC PUMPS.

No. 914,167.

Specification of Letters Patent.

Patented March 2, 1909.

Application filed January 22, 1908. Serial No. 412,168.

To all whom it may concern:

Be it known that I, JAMES W. NELSON, a citizen of the United States, and a resident of the city of New York, borough of Brooklyn, county of Kings, and State of New York, have invented certain new and useful Improvements in Pressure-Controlling Devices for Hydraulic Pumps, of which the following is a specification.

10 This invention relates to devices adapted to be interposed between means for generating hydraulic pressure and the requisite means for the application of such pressure—under conditions which render necessary or 15 desirable the employment of separate and relatively movable or adjustable devices for such generation and application—through the employment of which the workman or operator stationed where such pressure is 20 being applied, who is in position to note the progress and effect of the work, may directly control the generation of pressure and its application to the work to be done.

In an earlier application, filed January 20, 25 1908, Ser. No. 411,613, I have shown a device of the character above briefly outlined adapted for interposition between one or more rams and a hydraulic pump of the single-piston type. In another copending 30 application, filed January 20, 1908, Ser. No. 411,612, I have shown and described a device for similar interposition between a ram or rams and a hydraulic pump of the double-piston type.

35 The present invention contemplates the employment of a pump having more than two pistons, and for the purposes of this description I have shown a device of this character as applied to a triple-piston hydraulic pump.

40 It is well known that hydraulic jacks and pumps are frequently constructed with two and sometimes with three pistons having common operating means, with a view to the employment of both or all of said pistons 45 in order to rapidly raise the ram or rams to the point of contact with the work or load, after which one or more of the pumps are, in one manner or another, rendered inoperative, 50 so that a single piston, and invariably the smaller piston, alone is effectively operative, thus generating the maximum pressure of which the device is capable under the well-known principles of hydrostatics.

55 While the employment of a double-piston pump will generally meet ordinary require-

ments, it will be apparent that a triple-piston pump—or a pump having more than two pistons with common operating means—will have a still wider range of usefulness, inasmuch as one pump of this character may be made to suffice under a variety of conditions which would otherwise require two or more separate pumps. It is always desirable to raise the ram or rams to the point of contact with the work or load with the greatest possible speed, and it not infrequently happens that the preliminary effective pressure required is less than that ultimately desired, under which conditions, in the employment of a triple-piston pump, the operations of all three pistons would be made effective until the ram or rams were raised to contact with the load, after which, and during the period of lesser preliminary pressure, the larger pump would be rendered effectively inoperative until it became desirable to utilize the maximum power of which the pump was capable, for which purpose the next larger piston would be rendered effectively inoperative, the smaller piston alone operating to generate the increased pressure at a sacrifice of speed.

My invention will be more readily understood by reference to the accompanying drawings, forming a part of this specification, in which—

Figure 1 is a diagrammatic view, partly in section, of a complete apparatus embodying my invention; Fig. 2 is a plan view, partly in central section, of the individually-movable valve-container, and Fig. 3 is a transverse central section of Fig. 2.

Referring now to the drawings in detail, numeral 11 refers to a hydraulic pump which is provided with a central bore of varying diameters to provide for the three pistons 12, 13 and 14, respectively, these pistons being mounted upon a common piston-rod 15 which is reciprocated by means of the pump-lever 16 pivoted at 17 to the bracket 18 suitably mounted upon pump-block 11. I prefer that the pump 11 be mounted upon a base-plate 19 from which projects the arm 20 carrying the abutment-platform 21, by means of which the pump may be suitably braced against the operations of the pump-lever. The pump-block 11 is provided with a lateral duct 22 leading from the chamber below the larger and upper piston 12 to the exterior of said pump-block, where it is provided with means for the securing of a plug 23 for the

reception of the coupling or connection 24 at one end of the pipe 25. A similar duct 26 leads from the chamber below the second piston 13 to the plug 27 and through the connection 28 to the pipe 29, and a lateral duct 30 leads from the chamber below the lower and smaller piston 14 through the plug 31 and the connection 32 to the pipe 33.

Control of the flow during the pumping operation is effected through the employment of an individual member 34, which is preferably of cylindrical shape and of suitable metal, and which is provided with a bore 35 screw-threaded at its outer extremity for the reception of a correspondingly-threaded screw-plug 36 which provides the sealed chamber 37. This member 34 is further provided with a longitudinal central bore 38 leading from the chamber 37 to the end of said member where it is interiorly screw-threaded for the reception of a correspondingly-threaded screw-plug 39 which seals the end of said bore. The bore 38 is of smallest diameter throughout that portion adjacent to and leading into the chamber 37. At 40, this bore is increased in diameter to provide a seat for the valve 41 which has a stem 42 projecting from said valve into the chamber 37. At 43, the bore 38 is again increased in diameter to provide a seat for the valve 44 which has a stem 45 extending from said valve nearly but under normal conditions not quite to the valve 41. At 46, the bore 38 is again increased in diameter to provide a seat for the valve 47 which has a stem 48 extending from said valve nearly but under normal conditions not quite to the valve 44. In this portion of the bore 38 of greatest diameter, below the valve 47, I prefer to insert the removable cylindrical valve-plug 49, among other purposes to again reduce the effective diameter of said bore, and this plug 49 provides a seat for the valve 50 which has a stem 51 extending from said valve nearly but under normal conditions not quite to the valve 47. Between the valve 50 and the sealing plug 39 is provided a small chamber 52. The member or fitting 34 is provided with a longitudinal bore or duct 53 which communicates through the lateral duct 54 with the valve-bore 38 between the valves 41 and 44. The other end of the duct 53 communicates with the duct 55 in the laterally-projecting arm 56, the end of which is screw-threaded for the reception of a connection or coupling 67 at the end of the pipe 25 which leads to the larger pump-chamber. A similar longitudinal duct 58 communicates through the lateral duct 59 with the valve-bore 38 between the valves 44 and 47, while the other end of said duct 58 communicates with the duct 60 in the laterally-projecting arm 61, the extremity of which is similarly screw-threaded for the reception of a connection or coupling 57 at the end of the pipe 29

which is open to the middle pump-chamber. Another longitudinal duct 63 communicates through the lateral duct 64 with the valve-bore 38 between the valves 47 and 50, and the other end of said duct 63 is open to a duct 65 in the laterally projecting arm 66, the end of which is similarly screw-threaded for the reception of a connection or coupling 62 (diagrammatically shown in Fig. 1) at the end of the pipe 33 leading to the smaller pump-chamber. At the end of the fitting or member 34 opposite to the arms 56, 61 and 66, are the preferably branching arms 68 and 69 provided with the longitudinal ducts 70 and 71, respectively, which unite in the chamber 52. These arms are each screw-threaded at their extremities, for the reception of the couplings or connections 72 and 73 at the ends of the pipes 74 and 75, respectively. The pipe 74 leads through the coupling 76, the plug 77 and the duct 78 to the pressure chamber 79 underneath the ram 80 in the cylinder 81. Similarly, the pipe 75 leads through the connection 82 to the pressure-chamber underneath the ram 83 in the ram-cylinder 84, the latter device being in all essential respects identical to that comprising the ram 80 and ram-cylinder 81.

The screw-plug 36 is centrally bored to provide bearings for the short shaft 85, the outer end of which is provided with a head 86 having a slot for the reception of the bearing portion 87 of the lever 88. The inner end of the shaft 85 is provided with a cam 89 located in co-operative positional relation to the projecting end of the stem 42 of the valve 41. The cam 89 is so rotatively positioned that under normal conditions, with the lever 88 in the position indicated in Fig. 2, said cam is non-interferent with the ordinary automatic operation of the valve 41. Upon rotation of said shaft 85, by means of said lever 88, the cam 89 will first operate to impinge against the stem 42 of the valve 41 to unseat the latter and hold the same positively off its seat, without, however, interfering in any way with automatic action of the remaining valve in the series. Further rotation of said shaft 85, by turning said lever 88 through a slightly greater arc, will operate through said cam 89 to further advance the valve 41 in the direction of the valve 44 until the former impinges against the end of the stem 45 of said valve 44 and positively unseats the latter, holding the same off its seat without, however, interfering in any way with automatic action of the valves 47 and 50. In a similar manner, still further rotation of the cam 89 will cause the valve 44 to impinge against the stem 48 of the valve 47 and positively unseat the latter, the valves 41, 44 and 47 now being positively held off their seats while the valve 50 still retains its automatic function. Finally, the cam 89 may be still further rotated, whereupon the valve 47 will impinge

against the stem 51 of the valve 50 to positively unseat the latter, in which case all of the valves in the series will be held off their seats and an open passage provided from the 5 chamber 52 (and thus from each of the ram chambers) to the chamber 37. From this chamber 37 leads a lateral duct 90 (see dotted lines in Fig. 2) which leads through a nipple 91 to the rubber or other flexible tube or 10 hose 92 which leads thereto from any suitable source of liquid supply.

It will now be apparent that under what may be termed normal conditions—that is, with the lever 88 in the position indicated in Fig. 2 and the cam 89 non-interferent with automatic action of any of the valves in the series—upon the upstroke of the pump-lever 16 a partial vacuum will be created within the pump-chambers underneath the pistons 20 12, 13 and 14. The partial vacuum formed in the chamber underneath the piston 12 will cause an inequality of pressure which will result in the flow of liquid from the source of supply into the chamber 37 and 25 thence past the valve 41, which it unseats, into the duct 53, and thence through the pipe 25 into said pump-chamber. The partial vacuum in the chamber underneath the piston 13 will result in the flow of liquid from the 30 source of supply past the valves 41 and 42, in the bore 38, and through the duct 58 and the pipe 29 to said pump-chamber. The partial vacuum formed in the chamber underneath the piston 14, in a similar manner, will result 35 in the unseating of the valves 41, 44 and 47 and the flow of liquid past the same and into the duct 63, from whence it passes through the pipe 33 into the lower pump-chamber.

Upon the downstroke of the lever 16, the 40 liquid will be forced from the pump chambers respectively through the pipes 25, 29 and 33 to the valve-bore 38, but the excess of pressure is now in a direction to seat the valve 41. Flow back to the chamber 37 and 45 thence to the source of supply is now checked by said valve 41 and the liquid, under pressure of all three pumps is directed past the valve 50, which it unseats, into the chamber 52 and thence to the ram chambers underneath the rams 80 and 83. In this manner a maximum volume of liquid is forced into said ram-chambers at each stroke of the pump-lever, thus rapidly raising the ram or rams to the point of actual contact with the 55 work or load. Should it now be desirable to sacrifice speed for increased power to a certain but not the greatest extent, the operator at the ram will turn the lever 88 through an arc sufficient, in the manner described, to unseat the valve 41. The upper and larger pump-piston is now rendered effectively inoperative, inasmuch as the liquid which enters the chamber underneath the same is, upon the downstroke of the 60 lever 16—following the path of least resist-

ance—forced back into the chamber 37 and thence to the source of supply. The liquid under pressure of the two other pistons, upon the downstroke thereof, firmly seats the valve 44 against the liquid under the lesser 70 pressure of the larger piston 12. The two lower pumps only are now effectively operative, and under the well-known principles of hydrostatics the volume of liquid delivered to the ram chambers is decreased with a 75 resultant increase of power. Should it become desirable to still further increase this power, the operator at the ram (which, as will be remembered, is in the immediate proximity of the valve-containing member 80 or fitting) will turn the lever 88 through a slightly greater arc to effect, in the manner described, the unseating of both of the valves 41 and 44. Under these conditions, the pistons 12 and 13 are both rendered effect- 85 ively inoperative, the liquid from the chamber underneath the piston 12 following the course described in connection with the unseating of the valve 41 alone, and the liquid in the chamber underneath the piston 13, 90 the valve 44 being held off its seat, following the path of least resistance and flowing back past the now open valves 44 and 41 into the chamber 37 and thence to the source of supply. It will be seen that the lower and 95 smallest piston 14 now alone is effectively operative and, therefore, the pump is generating the maximum power of which it is capable, the liquid under pressure of this piston 14, which has been drawn from the 100 source of supply past the valves 41, 44 and 47, now effecting the seating of the valve 47 and being forced past the valve 50 into the chamber 52 and thence to the ram chamber or chambers.

When the ram or rams have been raised to the desired extent, and it is desired to remove or readjust these elements, the operator at the ram or rams will turn the lever 88 through a still greater arc, operating through 110 the cam 89 to unseat all of the valves in the series in the manner hereinbefore described. As stated, an open passage or passages is now provided from the ram chamber or chambers to the source of supply, and the weight of the 115 rams will force the liquid from the ram-chambers through this passage back to the source of supply to permit of the removal or readjustment mentioned.

All of the pipes 25, 29, 33, 74 and 75, 120 should be capable of withstanding a high pressure and should still be sufficiently flexible to permit of the movement of anyone of the respective elements of which the complete apparatus is composed, with respect to 125 another or others. As combining these features, I prefer to employ copper pipe. It is well known, however, that copper, when subjected to pressure for any long continued periods of time, acquires a certain brittle- 130

ness or temper which destroys its flexibility. Under such conditions, it is necessary to replace the pipe or subject the same to a more or less expensive process of annealing.

5 It will be apparent that when a device embodying my invention is employed, only the comparatively short lengths of pipe which connect the fitting 34 with the rams, are subjected to pressure continuously during the 10 progress of the work, the comparatively longer lengths of pipe, which connect pump and valve-container, being subjected to pressure only during the downstroke of the pump-lever 16. Therefore, by far the larger 15 proportion of the requisite amount of copper pipe employed is rendered much longer lived.

Many modifications of minor details of my improved pressure-controlling device for hydraulic pumps will doubtless readily suggest themselves to those skilled in the art to which it appertains, and I therefore do not desire to limit my invention to the specific construction herein shown and described.

I claim as new and desire to secure by 25 Letters Patent:

1. In combination, means for generating hydraulic pressure which include more than two pumps, means for applying the generated pressure, and means separate from both 30 of said elements for rendering effectively inoperative one or two or more of said pumps.

2. In combination, means for generating hydraulic pressure which include more than two pumps having common operating means, 35 means for applying the generated pressure, and means separate from both of said elements for rendering effectively inoperative one or two or more of said pumps.

3. In combination, means for generating 40 hydraulic pressure which include more than two pumps of different capacities, means for applying the generated pressure, and means separate from both of said elements for rendering effectively inoperative said pumps 45 from the largest to the smallest successively.

4. In combination, means for generating hydraulic pressure which include more than two pumps, means for applying the generated pressure, and means separate from both 50 of said elements for rendering effective the pressure of one of said pumps only or the combined pressures of two or more thereof.

5. In combination, means for generating hydraulic pressure which include more than 55 two pumps, means for applying the generated pressure, and means separate from both of said elements for rendering effective the pressure of one of said pumps only or the combined pressures of two or more thereof 60 and for rendering ineffective the operations of all of said pumps.

6. In combination, means for generating 65 hydraulic pressure which include more than two pumps, means for applying the generated pressure, and means separate from both

of said elements for rendering effective the pressure of one of said pumps only or the combined pressure of two or more thereof, for rendering ineffective the operation of all of said pumps and for relieving the pressure 70 in said applying means.

7. In combination, means for generating hydraulic pressure which include more than two pumps, separate means for applying the generated pressure at a selective point, and 75 means separate from both of said elements for rendering effectively inoperative one or two or more of said pumps.

8. In combination, means for generating hydraulic pressure which include more than two pumps, separate means for applying the generated pressure at a plurality of selective points, and means separate from both of said elements for rendering effectively inoperative one or two or more of said pumps. 80

9. In combination, means for generating hydraulic pressure which include more than two pumps, separate means for applying the generated pressure at a plurality of selective points, and means separate from both of 90 said elements for rendering effectively inoperative one or two or more of said pumps and for equalizing the pressures at the points of application.

10. In combination, means for generating 95 hydraulic pressure which include more than two pumps having common operating means, separate means for applying the generated pressure at a selective point, and means separate from both of said elements for rendering effectively inoperative one or two or more of said pumps. 100

11. In combination, means for generating hydraulic pressure which include more than two pumps having common operating means, 105 separate means for applying the generated pressure at a plurality of selective points, and means separate from both of said elements for rendering effectively inoperative one or two or more of said pumps. 110

12. In combination, means for generating hydraulic pressure which include more than two pumps having common operating means, separate means for applying the generated pressure at a plurality of selective points, 115 and means separate from both of said elements for rendering effectively inoperative one or two or more of said pumps and for equalizing the pressures at the points of application. 120

13. In combination, means for generating hydraulic pressure which include more than two pumps of different capacities having common operating means, means for applying the generated pressure, and means separate from both of said elements for rendering effectively inoperative said pumps from the largest to the smallest successively. 125

14. In combination, means for generating hydraulic pressure which include more than 130

- two pumps of different capacities having common operating means, separate means for applying the generated pressure at a selective point, and means separate from both of said elements for rendering effectively inoperative said pumps from the largest to the smallest successively. 5
15. In combination, means for generating hydraulic pressure which include more than two pumps of different capacities having common operating means, separate means for applying the generated pressure at a plurality of selective points, and means separate from both of said elements rendering effectively inoperative said pumps from the largest to the smallest successively. 10
16. In combination, means for generating hydraulic pressure which include more than two pumps of different capacities having common operating means, separate means for applying the generated pressure at a plurality of selective points, and means separate from both of said elements for rendering effectively inoperative said pumps from the largest to the smallest successively and for equalizing the pressures at the points of application. 15
17. In combination, means for generating hydraulic pressure which include more than two pumps of different capacities having common operating means, separate means for applying the generated pressure at a plurality of selective points, and means separate from both of said elements for rendering effectively inoperative said pumps from the largest to the smallest successively, for equalizing the pressures at the points of application and for relieving the applied pressures. 20
18. In combination, means for generating hydraulic pressure which include more than two pumps, separate means for applying the generated pressure, at a selective point, and means separate from both of said elements for rendering effective the pressure of one of said pumps only or the combined pressures of two or more thereof. 25
19. In combination, means for generating hydraulic pressure which include more than two pumps, separate means for applying the generated pressure at a plurality of selective points, and means separate from both of said elements for rendering effective the pressure of one of said pumps only or the combined pressures of two or more thereof. 30
20. In combination, means for generating hydraulic pressure which include more than two pumps, separate means for applying the generated pressure at a plurality of selective points, and means separate from both of said elements for rendering effective the pressure of one of said pumps only or the combined pressures of two or more thereof. 35
21. In combination, means for generating hydraulic pressure which include more than two pumps having common operating means, separate means for applying the generated pressure at a plurality of selective points, and means separate from both of said elements for rendering effective the pressure of one of said pumps only or the combined pressures of two or more of said pumps and for equalizing the pressures at the points of application. 40
22. In combination, means for generating hydraulic pressure which include more than two pumps having common operating means, separate means for applying the generated pressure at a selective point, and means separate from both of said elements for rendering effective the pressure of one of said pumps only or the combined pressures of two or more of said pumps. 45
23. In combination, means for generating hydraulic pressure which include more than two pumps of different capacities having common operating means, separate means for applying the generated pressure at a plurality of selective points, and means separate from both of said elements for rendering effective the pressure of one of said pumps only or the combined pressures of two or more thereof and for equalizing the pressures at the points of application. 50
24. In combination, means for generating hydraulic pressure which include more than two pumps, separate means for applying the generated pressure at a plurality of selective points, and means separate from both of said elements for rendering effective the pressure of one of said pumps only or the combined pressures of two or more thereof, for equalizing the pressures at the points of application and for rendering ineffective the operation of all of said pumps. 55
25. In combination, means for generating hydraulic pressure which include more than two pumps having common operating means, separate means for applying the generated pressure at a plurality of selective points, and means separate from both of said elements for rendering effective the pressure of one of said pumps only or the combined pressures of two or more thereof, for equalizing the pressures at the points of application and for rendering ineffective the operations of all of said pumps. 60
26. In combination, means for generating hydraulic pressure which include more than two pumps; separate means for applying the generated pressure at a selective point, and means separate from both of said elements for rendering effective the pressure of one of said pumps only or the combined pressures of two or more thereof and for relieving the pressure at the point of application. 65
27. In combination, means for generating hydraulic pressure which include more than two pumps, separate means for apply- 70 75 80 85 90 95 100 105 110 115 120 125 130

ing the generated pressure at a plurality of selective points, and means separate from both of said elements for rendering effective the pressure of one of said pumps only or 5 the combined pressures of two or more thereof and for relieving the pressures at the points of application.

28. In combination, means for generating hydraulic pressure which include more than 10 two pumps, separate means for applying the generated pressure at a plurality of selective points, and means separate from both of said elements for rendering effective the pressure of one of said pumps only or the combined 15 pressures of two or more of said pumps, for equalizing the pressures at the points of application and for relieving the applied pressures.

29. In combination, means for generating 20 hydraulic pressure which include more than two pumps having common operating means, separate means for applying the generated pressure at a plurality of selective points, and means separate from both of said elements for rendering effective the pressure of 25 one of said pumps only or the combined pressures of two or more of said pumps, for equalizing the pressures at the points of application and for relieving the applied pressures.

30. In combination, means for generating 30 hydraulic pressure which include more than two pumps having common operating means, separate means for applying the generated pressure at a selective point, and means separate from both of said elements for rendering effective the pressure of one of said pumps only or the combined pressures of two or more thereof and for relieving the pressure at the point of application.

40. 31. In combination, means for generating 40 hydraulic pressure which include more than two pumps of different capacities having common operating means, separate means for applying the generated pressure at a 45 plurality of selective points, and means separate from both of said elements for rendering effective the pressure of one of said pumps only or the combined pressures of two or more thereof, for equalizing the pressures at the points of application and for relieving the applied pressures.

32. In combination, means for generating 55 hydraulic pressure which include more than two pumps, separate means for applying the generated pressure at a plurality of selective points, and means separate from both of said elements for rendering effective the pressure of one of said pumps only or the combined pressures of two or more thereof, 60 for equalizing the pressures at the points of application, for rendering ineffective the operation of all of said pumps and for relieving the applied pressures.

33. In combination, means for generating 65 hydraulic pressure which include more than

two pumps having common operating means, separate means for applying the generated pressures at a plurality of selective points, and means separate from both of said elements for rendering effective the pressure 70 of one of said pumps only or the combined pressures of two or more thereof, for equalizing the pressures at the points of application, for rendering ineffective the operations of all of said pumps and for relieving the applied pressures.

34. In combination, a triple pump, a ram, a flexible conduit from each pump chamber and to the ram chamber, said conduits uniting in an individually movable member, 80 said member being provided with means for the supply of liquid to said conduits and with means for rendering said pumps successively inoperative.

35. In combination, a triple pump, a ram, 85 a flexible conduit from each pump chamber and to the ram chamber, said conduits uniting in an individually movable member, said member being provided with means for the supply of liquid to said conduits and 90 with means for rendering the pumps successively inoperative and with means for relieving the pressure in the ram chamber.

36. In combination, a triple pump, a plurality of rams, a flexible conduit from each 95 pump-chamber and to each ram-chamber, said conduits uniting in an individually movable member, said member being provided with means for the supply of liquid to said conduits and with means for rendering 100 the pumps successively inoperative.

37. In combination, a triple pump, a plurality of rams, a flexible conduit from each pump chamber and to each ram chamber, said conduits uniting in an individually 105 movable member, said member being provided with means for the supply of liquid to said conduits and with means for equalizing the pressures in the ram chambers and with means for rendering the pumps successively 110 inoperative.

38. In combination, a triple pump, a plurality of rams, a flexible conduit from each pump-chamber and to each ram-chamber, said conduits uniting in an individually- 115 movable member, said member being provided with means for the supply of liquid to said conduits, with means for equalizing the pressures in the ram chambers, with means for rendering one or two or all of said 120 pumps effectively inoperative and with means for relieving the pressures in the ram chambers.

39. In combination, a triple pump, a ram, a flexible conduit from each pump chamber 125 and to the ram chamber, said conduits uniting in an individually-movable member, a series of valves in said member, means for successively unseating said valves and thereby successively rendering the pumps 130

effectively inoperative, and means for supplying liquid to the pump chambers.

40. In combination, a triple pump, a ram, a flexible conduit from each pump chamber and to the ram chamber, said conduits uniting in an individually-movable member, a series of four valves in said member, the first checking back flow to one of said pumps, the second checking back flow to another of 10 said pumps, the third checking back flow to the remaining pump and the fourth check-

ing back flow from the final pressure chamber, and means for unseating one, two, three or all of said valves.

In testimony of the foregoing I have 15 hereunto set my hand in the presence of two witnesses.

JAMES W. NELSON.
